UNITED STATES PATENT OFFICE

FRANK J. OVEN, OF CHICAGO, ILLINOIS, ASSIGNOR TO VICTOR MANUFACTURING & GASKET CO., A CORPORATION OF ILLINOIS

SPARK-PLUG GASKET

Application filed November 1, 1929. Serial No. 404,106.

The present invention relates to improvements in gaskets and resides particularly in the provision of an improved spark plug gasket which is preferably formed entirely of sheet metal.

It is one of the principal objects of the present invention to provide a spark plug gasket preferably entirely metallic, and capable of convenient distortion thereof without fracture to conform to irregularities in the porcelain core or in the metal casing and retaining nut of spark plugs and to thereby form a better seal.

Another object of the present invention resides in the provision of a spark plug gasket formed entirely of a metal sheet, the usual asbestos filler or core commonly employed in gaskets of this type being eliminated.

It is a further object of the present invention to provide a novel gasket for spark plugs having a hollow core which permits the gasket to assume any desired shape as defined by the contour of the metal casing, retaining nut, or porcelain core of a spark plug.

Still another object of this invention is to provide a spark plug gasket which is efficient in use, simple in construction and inexpensive to manufacture.

The foregoing and such other objects and advantages as will become apparent as the description proceeds will be more readily understood from the following specification, reference being had to the accompanying drawings; in which:

Fig. 1 is a sectional elevational view of a spark plug employing the gaskets of this invention.

Fig. 2 is a perspective view of the improved spark plug gasket.

Fig. 3 is a central sectional view through the core of the improved gasket.

Fig. 4 is a sectional view, similar to Fig. 3,

showing the enveloping shell of the gasket prior to the insertion of the core.

Fig. 5 is an enlarged vertical sectional view through a fragment of the improved gasket before the enveloping shell is rolled over the core.

Fig. 6 is a similar vertical sectional view of a portion of a spark plug gasket showing the complete assembly thereof, taken on line 6-6 of Fig. 2.

Fig. 7 is a vertical sectional view similar to Fig. 6 showing a modified form of the spark plug gasket.

Gaskets of known construction employed in spark plugs are commonly provided with an asbestos filler, or if formed of one piece, are usually of solid construction, which construction prohibits adequate flexing or other distortion of the gaskets to conform to the porcelain core of the spark plug or to the shell or retaining nut thereof.

With the improved spark plug gasket, illustrated in the accompanying drawing, the provision of a novel hollow core permits ready flexing of said gasket, whereby the latter may conform or adjust itself to any irregularities present in the porcelain core or other contiguous parts of the spark plug.

Referring to the drawing, the novel spark plug gasket consists of an outer enveloping shell 11 pressed or otherwise formed from a metal sheet. The shell 11 is in the form of an annular ring, formed substantially U-shaped in cross section, having the bottom 12 and inner and outer side walls 13 and 14 substantially perpendicular to the bottom 12. An annular core 15 is adapted to be received within this channel shaped shell 11, said core also being formed of a metal sheet to assume a substantially triangular cross section having its annular edges abutting at the apex of the triangle, as at 16. The side 17 of the triangular core, opposite the apex is preferably formed arcuate in shape.

The core 15 is placed within the shell 11

with the apex 16 of the same disposed in contact with the portion 12 as shown particularly in Figures 5 and 6. With the core in this position the side walls 13 and 14 of the enveloping shell 11 are spun over upon and into contact with the arcuate surface 17 of said core.

Spark plug gaskets of this type are particularly adapted for use in spark plugs of 10 the type illustrated at 18 in Fig. 1. As shown, two gaskets are inserted in each spark plug, say, in the form shown in Fig. 6, one being held between the annular inner seat 19 of the shell 21 of the spark plug and the complementary annular seat 22 of the porcelain core 23. The other gasket is placed upon the annular outer seat 24 of the porcelain core and a retaining nut 25 is threaded into the shell 21 which nut contacts with and impinges 20 upon said upper gasket. When the nut 25 is tightened a pressure is exerted upon the gaskets perpendicular thereof tending to flatten or otherwise distort same. In some instances the distortion may be, if desired, so 25 great as to bring the gaskets to substantially the shape seen in Fig. 1.

The provision of the hollow core 15 in the gaskets affords convenient distortion thereof without fracture to conform to any irregularities which may be present in the seating surfaces 22 and 24 of the porcelain core 23. The ability of the improved gasket to distort and thus conform to the irregularities of the seating surfaces insures a perfect sealing of 35 the joints. As said gasket is compressed the side walls 13 and 14 are urged inwardly and outwardly respectively to abut the side walls of the porcelain core 23 and the shell 21, the triangular core acting as a filler and otherwise as a reinforcement to distribute pressures evenly on the sealing portions of the gasket and thus prevent fracture thereof.

While cores having various cross sectional areas may be employed, it is highly preferable 45 that the triangular cross section type be employed, as the gasket is considerably strengthened thereby and will, therefore, retain its shape under normal conditions, considerable pressure being required to distort 50 same.

However, if desired a gasket of the type such as shown in Figure 7 may be employed with similar results. In this form of the invention the core 27 thereof is preferably 55 formed of a metal sheet having its edges folded over upon itself and abutting at substantially the circumferential center line thereof, thus providing a relatively flat core of double thickness. These two thicknesses 60 of metal may be spaced apart slightly if desired to provide a hollow core but it is not essential, inasmuch as the double thickness thereof will permit a limited amount of flexing.

65 The enveloping shell 28 employed in this

form is similar in cross section to the core 27, this being formed of a metal sheet having its edges folded over and around the core 27 until its edges abut, as at 29.

A gasket of this type will retain a limited 70 amount of flexibility which will permit distortion thereof to allow said gasket to conform to the irregularities of the seating surfaces 22 and 24 of the porcelain core 23.

While there are numerous benefits obtainable 75 by employing the novel spark plug gaskets described herein, the principal advantage resides in the ability of the improved spark plug gasket to conform to distorted seating surfaces, thus compensating for the 80 irregularities in the seating surfaces of the porcelain and thereby preventing injury thereto.

While the preferred forms of the invention 85 have been shown and described in the foregoing, it is to be understood that the improved spark plug gaskets herein disclosed are capable of embodying various modifications 90 in detail structure without departing from the spirit of the invention, nor the scope of the appended claims.

I claim:

1. A spark plug gasket having, in combination, a split metallic core and a split shell enveloping said core, the seams of the 95 core and shell being disposed at non-adjacent points.

2. A spark plug gasket having, in combination, a split hollow metallic core and a split shell enveloping said core, the seams of the 100 core and shell being disposed at non-adjacent points.

3. A spark plug gasket having, in combination, a metallic core and an enveloping shell formed from a metal sheet having its 105 edges disposed in abutting relation, the core and shell each having a peripheral slit with the said slits positioned at remote points relative to each other.

4. A spark plug gasket having, in combination, a metallic core of substantially triangular-shaped cross section surrounded by a shell of rectangular cross section. 110

5. A spark plug gasket having, in combination, a metallic core of substantially 115 triangular-shaped cross section enveloped by a shell engaging its base and apex only.

6. A spark plug gasket having, in combination, a metallic core of substantially triangular cross section formed arcuate at the 120 side opposite the apex thereof, a shell enveloping said core and engaging the arcuate surface and apex thereof only.

7. A spark plug gasket having, in combination, a hollow metallic core of substantially triangular cross section, with the walls thereof at its apex normally spaced apart and a shell of polygonal cross section enveloping 125 said core, the core and shell having seams positioned at remote points from each other. 130

8. A spark plug gasket having, in combination, a core formed from a metal sheet into substantial triangular cross section, the ends of which abut at the apex of the section,
5 and an enveloping shell of polygonal cross section encompassing said core, the sheet and shell having each a seam with the seams disposed at remote distances from each other whereby leakage is prevented.
10. In testimony whereof I affix my signature
at 10 South La Salle Street, Chicago, Illinois.
